UNITED STATES PATENT OFFICE.

HARRY C. JONES, OF LARCHMONT, NEW YORK, ASSIGNOR TO LITHOPRINTEX CORPORATION, OF NEW YORK, N. Y., A CORPORATION OF NEW YORK.

APPARATUS FOR AND METHOD OF PRINTING FROM PHOTOGRAPHIC PLATES ONTO SENSITIZED SURFACES.

Application filed February 24, 1923. Serial No. 620,869.

This invention relates to apparatus for and method of printing from a photographic plate onto a sensitized surface and more particularly onto such sensitized surfaces as are formed on metallic plates such as zinc. The invention is particularly well adapted to be used in cases where it is desired to print from a portion only of said photographic plates onto a marginal portion of said sensitized surfaces.

A principle object of the invention is to provide an efficient and reliable method of and means for firmly and positively holding said plate in printing engagement when only a portion of said plate superposes said surface.

The invention consists in the method herein described according to the preferred manner of carrying out the same and in the novel features of construction, combination and arrangement of parts of the apparatus for carrying out the same and hereinafter described in connection with the present preferred embodiment of the same. And the invention will be more particularly pointed out in the appended claims.

Further advantages and uses will appear from the following description taken in connection with the accompanying drawings illustrating by way of example the present preferred embodiment of the apparatus wherein:

Fig. 1 shows in plan view a support bearing a sensitized surface and a yieldable surface forming an extension thereof.

Fig. 2 shows a sectional view taken at 2-2 of Fig. 1, and in proper relation thereto is shown a section of a printing frame.

Fig. 3 is a side elevation corresponding to Fig. 1.

Referring to the drawings in which like numerals denote the same members in the various views and more particularly to Fig. 2, a support or table 1 has mounted thereupon a suitable sensitized sheet or plate such as the zinc plate 2 having a sensitized surface 3. A frame 4 is attached to the support by screws 5 to form an extension of the support. Lying upon this frame and supported thereby is a mat or sheet 6 designated as being composed of a yieldable material such as rubber; but it is to be understood that other materials can readily be used.

The upper face or surface of the rubber sheet 6 is so arranged that it forms in effect a continuation of the zinc plate surface for receiving and supporting such portion of a printing frame 7 as may project from the zinc plate. This rubber sheet 6 may either be placed in juxtaposition to a single side or end of support 1 or may be notched out and act as a boundary on two sides for a portion of the sensitized plate and its support.

Any suitable form of vacuum frame may be used for printing from a photographic plate on to the marginal portion of this sensitized surface. I prefer a frame of the type which will have the negative secured thereto. One type of such frame is shown in Fig. 2 where the printing frame 7 is shown lying over adjacent portions of the sensitized plate 2 and the sheet or surface 6. A sealing member 8 cooperates with said frame 7 for sealing off a space beneath said frame as defined by said seal 8. A photographic plate 10 may be attached to frame 7 by any suitable means such as by a part 9 cemented to the negative and slidably in a groove 9', which allows plate 10 a relative movement with respect to a transparent plate 18 which lies over plate 10 and serves to press plate 10 down as will be hereafter described. This plate 18 is sealed to the frame 7 by rubber strips 19. A member such as 11 is connected to 7 and communicates with space 12 through which air may be exhausted from said space and likewise from spaces 13 and 14.

Frame 7 is not claimed per se as this is the subject matter of my co-pending application Ser. No. 615,487, filed January 29, 1923 and, therefore, no further description of it is here necessary.

The apparatus of this invention and the method of operating the same apply particularly to that class of work wherein it is desired to print a portion of a photographic plate or an object therefrom onto a marginal portion of a sensitized surface such as is commonly placed on a zinc or other suitable metallic backing. In such cases it is customary to secure the zinc or metallic plate bearing the sensitized surface upon a suitable support of approximately the size of the zinc plate such as is represented at 1, and then superpose a photographic plate and

print from the photographic plate on to the sensitized surface. Where a portion only of such photographic plate is to be printed onto a marginal portion of said sensitized surface, great difficulty and inaccuracy have heretofore been experienced. By marginal portion is meant a portion bounded by one or more sides of said sensitized surface and less than the area of the printing frame. It will, therefore, be seen that, as shown in Fig. 1, if it is desired to print from a photographic plate such as 10 onto the marginal portion 15 as defined by the dash lines 16 and 17, the frame 7 will project beyond the plate 2 and it will be impossible to form an airtight seal with the sealing member 8 without such means as is provided by this invention.

According to the present invention I effect supply an extension to that marginal portion of the sensitized surface to be printed upon so as to form a sealing seat for the vacuum frame and then place the negative and vacuum frame over the combined adjacent portions of the sensitized surface and said extension, seal the same in position and exhaust the air and force the negative down on the combined adjacent surfaces.

The operation of this apparatus is as follows. The sensitized plate 2 is placed on support 1 and the auxiliary frame 4 is secured in position adjacent the portion of the zinc plate to be printed upon. The mat 6 is then placed into juxtaposition with one or more sides of the sensitized surface so that the surface of 6 forms in effect a continuation of the surface 3, the combined surfaces forming a sufficient seat for the sealing member 8 operated in connection with and preferably carried by frame 7. Frame 7 is then placed over the desired adjacent portions of surfaces 3 and 6 with the photographic plate 10 interposed and preferably carried by said frame 7. The space 12 of frame 7 is then connected to an exhauster or vacuum pump by suitable means as 11 and the air is exhausted from spaces 12, 13 and 14, thus forcing the plate 18 downward and it in turn pressing photographic plate 10 into engagement with said covered surfaces. The printing is then done in the manner well known in the art.

Having thus described my invention with particularity with reference to the preferred method of carrying out the same and in connection with the preferred apparatus for carrying out the same, it will be obvious to those skilled in the art, after understanding my invention, that other changes and modifications may be made therein without departing from the spirit and scope of my invention, and I aim in the appended claims to cover all such changes and modifications as are within the scope of the invention.

Having thus described my invention what

I claim and desire to secure by U. S. Letters Patent is:—

1. In apparatus of the character described, the combination of a support for a sensitized surface, means operatively related thereto forming an extension thereof and having a surface forming in effect a continuation of a portion of the sensitized surface, a vacuum frame for printing from a photographic plate onto said portion of the sensitized surface, means for sealing off from the atmosphere said portion of the sensitized surface and such part of the adjacent surface as coincides with said printing frame, and means of communication for exhausting the air from over the sealed off surfaces to force the photographic plate into contact with said portion of the sensitized plate. 75

2. In apparatus of the character described, the combination of a support for a sensitized surface, means operatively related thereto forming an extension thereof and having a yieldable surface forming in effect a continuation of a portion of the sensitized surface, a vacuum frame for printing from a photographic plate onto said portion of the sensitized surface, means for sealing off from the atmosphere said portion of the sensitized surface and such part of the adjacent surface as coincides with said printing frame, and means of communication for exhausting the air from over the sealed off surfaces to force the photographic plate into contact with said portion of the sensitized plate. 90

3. In apparatus of the character described the combination of a support for a sensitized surface, means operatively related thereto, and a yieldable surface mounted on said means and forming in effect a continuation of a portion of the sensitized surface, a vacuum frame for printing from a photographic plate onto said portion of the sensitized surface, means for sealing off from the atmosphere said portion of the sensitized surface and such part of the adjacent surface as coincides with said printing frame, and means of communication for exhausting the air from over the sealed off surfaces to force the photographic plate into contact with said portion of the sensitized plate. 105

4. In apparatus of the character described, the combination of a support for a sensitized surface, means operatively related thereto forming an extension thereof and having a surface forming in effect a continuation of a portion of the sensitized surface, a vacuum frame for printing from a photographic plate onto said portion of the sensitized surface, means on said frame for holding a photographic plate, means for sealing off from the atmosphere said portion of the sensitized surface and such part of the adjacent surface as coincides with 110

said printing frame, and means of communication for exhausting the air from over the sealed off surfaces to force the photographic plate into contact with said portion of the sensitized plate.

5. In apparatus of the character described, the combination of a support for a sensitized surface, means operatively related thereto forming an extension thereof and having a 10 surface forming in effect a continuation of a portion of the sensitized surface, said means bounding a portion of said sensitized plate on two sides, a vacuum frame for printing from a photographic plate onto said portion 15 of the sensitized surface, means for sealing off from the atmosphere said portion of the sensitized surface and such part of the adjacent surface as coincides with said printing frame, and means of communication 20 for exhausting the air from over the sealed off surfaces to force the photographic plate into contact with said portion of the sensitized plate.

6. In apparatus of the character described, the combination of a support for a sensitized surface, means operatively related thereto forming an extension thereof and having a surface forming in effect a continuation of a portion of the sensitized 25 surface, a vacuum frame for printing from a photographic plate onto said portion of the sensitized surface, means operatively related to said sensitized surface said frame and said photographic plate and serving to seal 30 off from the atmosphere that portion of the sensitized surface covered by the photographic plate, and means of communication for exhausting the air from over the sealed off surfaces to force the photographic plate 35 into contact with said portion of the sensitized plate.

7. The method of printing from a portion 40 of a photographic plate onto a marginal portion of a sensitized surface, which comprises 45 providing a surface adjacent said portion of the sensitized surface to form in effect a continuation of said portion of the sensitized surface for the purpose of accommodating that portion of a vacuum printing frame 50 and the photographic plate which projects beyond said portion of the sensi-

tized surface, sealing off from the atmosphere the portion of the sensitized plate and the portion of the extended surface covered by said printing frame, exhausting the air 55 from said sealed off space to force the photographic plate into engagement with said covered surfaces, and printing from the photographic plate onto the corresponding marginal portion of the sensitized plate. 60

8. The method of printing from a portion of a photographic plate onto a portion of a sensitized surface which comprises placing a plane surface in juxtaposition to a part of said sensitized surface, so that said plane 65 surface will form in effect a continuation of a part of said sensitized surface and the combined surfaces present in effect a plane surface sufficient to accommodate said printing frame, placing a vacuum printing frame 70 with sealing engagement upon adjacent portions of said sensitized surface and extension, exhausting the air from the sealed off space between said photographic plate and said combined surfaces to thereby force said 75 photographic plate into printing engagement with said sensitized surface, and printing from said photographic plate onto said portion of the sensitized surface.

9. The method of printing from a portion 80 of a photographic plate onto a portion of a sensitized surface which comprises placing a yieldable surface in juxtaposition to a part of said sensitized surface so that said yieldable surface will form in effect a continuation of a part of said sensitized surface for supporting a printing frame and the combined surfaces present in effect a surface suitable to accommodate said printing frame, placing a vacuum printing frame 85 with sealing engagement upon adjacent portions of said sensitized surface and yieldable surface, exhausting the air from the sealed off space between said photographic plate and said combined surfaces to thereby force 90 said photographic plate into printing engagement with said sensitized surface, and printing from said photographic plate onto said portion of the sensitized surface. 95

In testimony whereof I have signed my 100 name to this specification.

HARRY C. JONES.
